UNITED STATES PATENT OFFICE.

JOSEPH F. SCHEUER, OF TWO RIVERS, WISCONSIN.

Thermal Circuit-Closer.

1,076,394.

Specification of Letters Patent. Patented Oct. 21, 1913.

Application filed May 5, 1913. Serial No. 765,718.

To all whom it may concern:

Be it known that I, JOSEPH F. SCHEUER, a citizen of the United States, and resident of Two Rivers, in the county of Manitowoc and State of Wisconsin, have invented certain new and useful Improvements in Thermal Circuit-Closers; and I do hereby declare that the following is a full, clear, and exact description thereof.

10 My invention consists in what is herein particularly set forth with reference to the accompanying drawings and pointed out in the claims of this specification.

Like in my now allowed application Serial No. 747,149, filed February 8, 1913, the object of the present invention is to provide simple, economical and efficient thermal circuit-closers of the fusible type and which are applicable as parts of automatic electric-20 signaling apparatus to be individually operative in the event of an increase of temperature in the vicinity thereof beyond a predetermined degree, the construction of said circuit-closers being such as to facilitate 25 testing of a line in which any one of the same is utilized.

Figure 1 of the drawings represents a sectional view of a fusible thermal circuit-closer in accordance with my invention attached to a support, the plane of the section being indicated by line 1—1 in the other 30 illustrations; Fig. 2, a front elevation of the same partly broken away, and Fig. 3, a rear elevation of said circuit-closer.

35 Referring by numerals to the drawings, 4 indicates an insulator-block, circular or otherwise, the front of which is countersunk and provided with a central recess 5 of suitable dimensions between apertures 6 through 40 which extend screws 7 by which said block is attached to a support. The rear of the insulator-block is also recessed parallel to its recess 5 and preferably partitioned at 8 whereby two rear recesses are provided, the

45 same being open at their outer ends where said block is preferably slabbed back of a partition 9 thereof that intervenes between its front and rear recesses.

Engaging the rear recessed portion of the 50 block are opposite right-angle conductor-brackets 10 and these brackets are shown held in place by screws 11, 11', that extend through apertures provided in the partition 9 of said block, it being preferable to interpose a suitable waterproof material 12 between said brackets and partition. By

means of the screw 11, a spring-contact plate 13 is fastened in the recess 5 of the insulator-block to close on the screw 11', and binding-screws 14 for electric-current 60 distribution wires 15 are provided in connection with the brackets 10. Set in the front countersink of the insulator-block and preferably against a suitable waterproof material 16 is a preferably thin brass disk 17 65 provided with apertures registrable with those 6 of said block for the passage of the attaching screws aforesaid.

The partition 9 of the insulator-block is provided with an aperture 18 (shown in 70 Fig. 3) through which to pass a tool from the rear in order to retract the spring-contact 13 from closed to open position against the disk 17, and said disk is provided with an aperture through which to solder said 75 contact to said disk, the solder 19 being fusible at a temperature of the predetermined degree aforesaid. Subsequent to the soldering operation, the aperture 18 in the partition 9 of the insulator-block is preferably 80 filled with a plug 20 of suitable waterproof material, as shown in Fig. 1. By the employment of waterproof material in the insulator-block as above specified, the circuit-closer is strictly weatherproof and 85 adaptable where damp or even water exists, and the circuit-closer is for connection in parallel with other devices of an electric signaling apparatus not shown.

In practice, the melting away of the solder 90 19 will result in the freed end of the spring-contact 13 closing on the head of the opposing screw 11', and in consequence thereof to effect an energization of the electric signaling apparatus. At any time it is desirable to test the line, the screw 11' and the 95 disk 17 or solder 19 may be temporarily connected by a suitable bridge applied thereto.

I claim:

1. A thermal circuit closer comprising an insulator-block attachable to a support and provided with front and rear parallel recesses, a pair of conductor-brackets in the rear recessed portion of the block for connection with electric-current distribution-wires, a spring-contact in the front recess of said block electrically connected to one of the brackets and opposed to an electric-conductor provided in connection with the 105 other of said brackets, a front recess cover, and solder by which a fusible union is estab- 110

lished between said contact and cover through an aperture in the latter to normally hold the former in open circuit position, the block being apertured to provide 5 for the insertion of a retracting tool back of the aforesaid contact.

2. A thermal circuit closer comprising an insulator-block attachable to a support and provided with front and rear parallel recesses, a pair of conductor-brackets in the rear recessed portion of the block for connection with electric-current distribution-wires, waterproof material intermediate of the brackets and block, a spring-contact in 10 the front recessed portion of said block electrically connected to one of the brackets and opposed to an electric-conductor provided in connection with the other of said brackets, a front recess cover, waterproof material 15 interposed between the cover and block, similar material by which an aperture in the block back of the spring-contact is plugged, and solder by which a fusible union is established between said spring-contact and cover 20 through an aperture in the latter to normally hold the former in open circuit position.

3. A thermal circuit-closer comprising an insulating-block provided with a front recess and a partitioned rear recess parallel to the one aforesaid, a pair of conductor-brackets in the rear recessed portion of the block in opposite directions from the partition for connection with electric-current distribution-wires, bracket securing screws extending from within the front recess of said 30 block, a spring-contact fastened in said front 35

recess of the block by one of the screws to close upon the other of said screws, a recess cover, and solder by which a fusible union 40 is established between said contact and cover through an aperture in the latter to normally hold the former in open circuit position, the block being apertured to provide 45 for the insertion of a retracting tool back of the aforesaid contact.

4. A thermal circuit-closer comprising a forwardly countersunk insulator-block provided with a front recess and a partitioned rear recess parallel to the one aforesaid, a pair of conductor-brackets in the rear recessed portion of the block in opposite directions from the partition for connection with electric-current distribution wires, a spring-contact in the front recess of said 50 block electrically connected to one of the brackets and opposed to an electric-conductor provided in connection with the other of said brackets, a disk set in the countersink of the block, and solder by which a fusible 55 union is established between said contact and disk through an aperture in the latter to normally hold the former in open circuit position, the block being apertured to provide 60 for the insertion of a retracting tool back of the aforesaid contact.

In testimony that I claim the foregoing I have hereunto set my hand at Two Rivers, in the county of Manitowoc and State of Wisconsin in the presence of two witnesses. 70

JOSEPH F. SCHEUER.
